Primary Examiner—Cathron C Brooks*Assistant Examiner*—Kevin K Rudzinski(74) *Attorney, Agent, or Firm*—Jean C. Edwards, Esq.; Akerman Senterfitt LLP(57) **CLAIM**

The ornamental design for a light reflector, as shown and described.

DESCRIPTION

FIG. 1 is a perspective view of the front and bottom of a light reflector showing my new design;

FIG. 2 is a perspective view of the rear and bottom thereof;

FIG. 3 is a front view thereof;

FIG. 4 is a rear view thereof;

FIG. 5 is a top plan view, a bottom view being a mirror image thereof; and,

FIG. 6 is a right side view, a left side view being a mirror image thereof.

The broken lines immediately adjacent to shaded surfaces identify the bounds of the claimed design and form not part of the claimed design. The remaining broken lines show unclaimed internal environmental structures shown through an unclaimed surface and form no part of the claimed design.
